UNITED STATES PATENT OFFICE.

WILLIAM F. HENDRY, OF NEW YORK, N. Y., ASSIGNOR TO WESTERN ELECTRIC COMPANY, OF CHICAGO, ILLINOIS, A CORPORATION OF ILLINOIS.

AUTOMATIC MOTOR-STARTER.

No. 836,036.

Specification of Letters Patent.

Patented Nov. 13, 1906.

Application filed October 16, 1905. Serial No. 282,995.

To all whom it may concern:

Be it known that I, WILLIAM F. HENDRY, a citizen of the United States, residing at New York, in the county of New York and State of New York, have invented a certain new and useful Improvement in Automatic Motor-Starters, of which the following is a full, clear, concise, and exact description.

My invention relates to a device for gradually and safely regulating the flow of current through a motor when it is being started in motion, and has for its object the automatic short-circuiting of the starting resistance of an electric motor.

Various means have been devised for first admitting a weak current to the motor and gradually increasing the current until the full strength for which the motor is adapted is reached. It has been customary to include resistances in the armature-circuit, through which the current first flows when the switch is closed, and to gradually cut out the resistances after the motor has started. One well-known means comprises a series of electromagnets arranged to be successively operated as the counter electromotive force of the motor increases and so connected as to control the resistance in the motor-circuit. The various methods hitherto devised for gradually cutting out the starting resistance, however, are open to more or less serious objections.

In my invention the solenoids which operate the switch for short-circuiting the steps or blocks of resistance are adapted to operate successively upon the closing of the motor main switch, said solenoids being controlled by a relay whose actuating-coil is in series with the armature-circuit and which is therefore itself controlled by the fluctuations of the current in the motor-armature. This allows of rapid acceleration under a light load and very gradual acceleration under a heavy load, resistance being cut out at exactly the proper moments in a step-by-step method until the full current strength for which the motor is adapted is reached.

I will describe my invention more particularly by reference to the accompanying drawings, in which—

Figure 1 is a diagram showing the course of the main and shunt currents through the motor and starting device, the actuating-coils of the resistance-solenoids being con-

nected across the line in series. Fig. 2 is a modified form of the arrangement shown in Fig. 1, by which the controlling-relay is short-circuited when the entire armature resistance is cut out. Fig. 3 is a diagram of the circuits of my invention, showing the actuating-coils of the resistance-solenoids connected in parallel across the line.

The same letters of reference are used to designate the same parts wherever they are shown.

As illustrated in the drawings, when the switch is closed to connect the motor with the mains the current from the terminals will be closed through armature resistance R' , relay S , and armature-motor M . The resistance R' is arranged in a plurality of steps or blocks. The strength of current flowing through solenoids $S' S^2 S^3$ is controlled by relay S . The plungers of said solenoids operate switches $s' s^2 s^3$, respectively, for successively cutting out the steps or blocks of resistance R' . While for purpose of description I have shown the armature resistance arranged in three blocks and adapted to be cut out by three switches, it is obvious that any desired number of blocks and switches may be used.

The relay S , which is in series with the armature-circuit, is adjustable, so that it may be arranged to operate at any desired current.

In Figs. 1 and 2 a system is illustrated in which both series and shunt fields of the motor are employed. In said figures the windings of the solenoids are shown connected across the line in series with each other and in series with a parallel circuit, one branch of which has a resistance R^2 and the other branch has two switches, one controlled by the solenoid S^3 and the other by the relay S . When the resistance R^2 is inserted, it prevents the solenoids $S' S^2 S^3$ from receiving enough power to operate the switches $s' s^2 s^3$, though it permits sufficient current to pass to hold the switches firmly closed after they have been once lifted to a closed position.

Referring to Figs. 1 and 2, the operation of my step-by-step automatic motor-starter is as follows: When the main switch is closed, the current flows through the armature and the starting resistance R' , which allows a current to pass of any predetermined amount—say about fifty per cent. above the normal running-current of the motor. The relay S

is adjusted to operate at this current and opens the contact a , which opens the short circuit around the resistance R^2 . The resistance R^2 is thus inserted in the branch circuit 5 in series with the solenoids S' S^2 S^3 and is of such value as not to permit a flow of current of sufficient strength to operate any of said solenoids. As the motor-armature speeds up the flow of current in the circuit including relay S is reduced thereby and the relay S releases its armature, thus closing contact a and short-circuiting resistance R^2 . This increases current through solenoids S' S^2 S^3 , which are arranged to operate at different 10 current strength. Enough current passes through solenoid S' to lift its plunger and close switch s' , thereby cutting out one step or block of the starting resistance R' . As a result the current through the armature-circuit increases quickly to fifty per cent. above normal, the relay S again operates as before, and the resistance R^2 is again inserted in the branch circuit of the solenoids before the 15 current through the solenoid-circuit has increased sufficiently to lift the plunger of another solenoid. The resistance R^2 reduces the current through said solenoids sufficiently to prevent further operation of the solenoids, but permits the flow of enough current to hold the switch s' firmly in place. When the current through the armature again dies down, owing to the motor speeding up, the relay S again releases its armature, thereby closing the short circuit around 20 resistance R^2 , and the solenoid S^2 operates to close the switch s^2 , thereby cutting out a second block of the resistance R' . Thereupon the flow of current through the armature-circuit immediately increases to operate the 25 relay S to insert the resistance R^2 in the solenoid-circuit. The flow of current through the solenoids is then sufficient to hold the switches s' s^2 closed, but is insufficient to close the switch s^3 . The above cycle of operations continues until the resistance R' is by 30 this step-by-step method entirely cut out as the motor gets up to speed.

When the solenoid S^3 closes the switch s^3 and cuts out the last block of the armature 35 resistance, the plunger of said solenoid opens the switch b , thereby inserting resistance R^2 in the solenoid-circuit in order to protect the resistance-solenoids S' S^2 S^3 from excessive heating.

55 In Fig. 2 I have shown a short circuit for relay S , said short circuit being closed when the solenoid S^3 closes its switch to cut out the last block of the resistance.

In Fig. 3 I have shown my invention with 60 the actuating-coils of the solenoids S' S^2 S^3 connected across the line in parallel with each other and in series with a parallel circuit, one branch of which has the resistance R^2 and the other branch a contact a' , controlled by the armature of the relay S .

Referring to Fig. 3, the operation of the starter in cutting out the resistance R' is substantially the same as that already described. When the main switch is closed, the current flows through the resistance R' , the relay S , 70 and the motor-armature M . Immediately the relay S attracts its armature and opens contact a' . The current in the branch circuit flowing through the resistance R^2 and the coil of solenoid S' is insufficient to actuate said solenoid. However, when the flow of current in the armature-circuit dies down as the motor speeds up the relay S drops its armature and the resistance R^2 is short-circuited. The solenoid S' thereupon operates 75 the switch s' to cut out a portion of the armature resistance. As soon as the solenoid s' pulls up its plunger the top of said solenoid-frame is energized and the solenoid S^2 , whose coil is electrically connected to the frame of solenoid S' , is included in the branch circuit in parallel with S' and receives current; but since the cutting out of a block of the resistance R' increases the flow of current through 80 relay S said relay is operated to again include the resistance R^2 in the branch circuit, owing to which the current flowing through the coil of solenoid S^2 is insufficient to actuate it. As soon as the solenoid S^2 raises its plunger the solenoid S^3 is likewise thrown in 85 parallel with solenoids S' and S^2 .

When in the arrangement shown in Fig. 3 enough current passes through the solenoid S^3 to lift its plunger and cut out the entire resistance R' , said plunger also operates a 90 switch c , thereby opening the circuit to solenoid S' , which in turn opens the circuit to solenoid S^2 . S^3 is therefore the only solenoid 95 whose coil receives current after the motor is up to speed, at which time a resistance R^3 is inserted in series with the solenoid S^3 to protect the same.

It will be observed that when the solenoids are connected in series, as illustrated in Figs. 1 and 2, all of said solenoids receive current after the armature resistance has been entirely cut out, whereas when said solenoids are connected in parallel, as illustrated in Fig. 3, only one coil receives current after the armature resistance is short-circuited. It 105 will also be observed that both in Figs. 2 and 3 the relay S is short-circuited with the last step of resistance.

If when any switch closes and cuts out a block of the starting resistance the current 110 in the armature-circuit does not increase to the desired amount above the normal running-current of the motor by reason of a very light load or any other cause, then the armature of relay S will remain unattracted and 115 allow one or more of the other solenoids to operate until enough resistance is cut out to increase the current to the predetermined amount. If, on the other hand, the motor-current should not fall as the speed of the 120

125 130

revolution of the armature increases, by reason of some defect in the motor or on account of an excessive load, the relay-armature will remain attracted, and therefore the cutting out of any resistance will be impossible.

Thus my invention provides simple means for regulating safely and automatically the flow of current through the motor-armature.

I claim—

- 10 1. In a motor-starting device, the combination with the motor, of a resistance included in the circuit of the motor-armature, a branch circuit including a plurality of solenoids adapted to operate at different current strength, switches operated by said solenoids for successively cutting out steps of said resistance, and a single relay in series with the armature-circuit and controlled by the fluctuations in the motor-current for directly controlling the flow of current through said solenoids.

- 25 2. In a motor-starting device, the combination with the motor, of a resistance and a relay included in the circuit of the motor-armature, switching means controlled by said relay for successively cutting out steps of said resistance, and a short circuit for said relay closed when said resistance is entirely cut out.

- 30 3. The combination with a motor having a starting resistance in its armature-circuit, of a plurality of solenoids connected across the line in parallel with each other, switches controlled by said solenoids for successively cutting out steps of said resistance, and a single relay in series with the armature-circuit and controlled by the fluctuations in the motor-current for controlling the flow of current through said solenoids.

- 40 4. The combination with a motor having a starting resistance in its armature-circuit, of a plurality of solenoids connected across the line in parallel with each other, switches controlled by said solenoids for successively cut-

ting out steps of said resistance, a relay in 45 series with the armature-circuit controlling the flow of current through said solenoids, and means operated by one of said solenoids for short-circuiting said armature resistance, said relay and the other of said solenoids. 50

5. The combination with a motor having a starting resistance in its armature-circuit, of a plurality of solenoids adapted to operate at different current strength and having a resistance in their circuit, a relay in series with 55 the armature-circuit and controlled by the fluctuations of the motor-current to cut in or out said solenoid resistance, switches operated by said solenoids for successively cutting out steps of said armature resistance, and means whereby the operation of the slowest-acting solenoid inserts resistance in the solenoid-circuit. 60

6. The combination with a motor having a starting resistance in its armature-circuit, of 65 a plurality of solenoids adapted to operate at different current strength and having a resistance in their circuit, means in series with the armature-circuit and controlled by the fluctuations of the motor-current to cut in or out said solenoid resistance, and switches operated by said solenoids for successively cutting out steps of said armature resistance. 70

7. The combination with a motor, of a starting resistance in its armature-circuit, a 75 plurality of solenoids adapted to operate at different current strength, switches, for successively cutting out steps of said resistance, controlled by said solenoids, a resistance in the circuit of said solenoids, and a relay in 80 the armature-circuit for controlling said resistance in the solenoid-circuit.

In witness whereof I hereunto subscribe my name this 10th day of August, A. D. 1905.

WILLIAM F. HENDRY.
